UNITED STATES PATENT OFFICE.

CHARLES L. INGALLS, OF LOWELL, MASSACHUSETTS, ASSIGNOR OF ONE-HALF TO GEORGE F. BLAIR, OF SAME PLACE.

LAMP-CHIMNEY.

SPECIFICATION forming part of Letters Patent No. 380,801, dated April 10, 1888.

Application filed June 26, 1885. Serial No. 169,819. (No model.)

To all whom it may concern:

Be it known that I, CHARLES L. INGALLS, of Lowell, in the county of Middlesex and State of Massachusetts, a citizen of the United States, 5 have invented a new and useful Improvement in Lamp-Chimneys, of which the following is a full, clear, and exact description, reference being had to the accompanying drawings, forming a part of this specification, in explaining 10 its nature.

It is well known that lamp-chimneys are liable to be broken in use because of the rapid variation in temperature to which they are subjected, the glass being often highly heated, 15 and while thus heated if subjected to the influence of cold it cracks.

The object of my invention is, primarily, to prevent this breakage. It further, however, improves the light-giving qualities of the lamp 20 to which the improvement is applied.

In the drawings, Figure 1 is a view in elevation showing the features of my invention. Fig. 2 is a view in plan of the spring-clamp.

Referring to the drawings, A represents the 25 burner; B, the chimney; C, the flame of the lamp; D, the flue formed by the tube, pipe, or casing *d*, which I prefer shall be shaped into a bell-mouth, arranged immediately above the burner and at a proper height therefrom.

30 The caliber of this flue *d* must be such as to efficiently carry off the products of combustion, and must be so much smaller than the caliber of the chimney as to leave a considerable space for the passage of air down the chimney from the outside of this flue D. The 35 material of which this flue D is made should be such as would be comparatively refractory under the heat to which it is exposed. It would be ordinarily of sheet metal or asbestos 40 board.

The flue is supported within the chimney by means of arms F, which are secured to the tube or pipe *d*, and have at their lower ends semicircular jaws *f*, which shut upon or clasp 45 the base of the burner. These arms are preferably spring-arms, and are adapted to clasp the burner firmly enough to prevent the oscillation of the flue in moving the lamp. The

presence of this interior flue establishes a downward draft within the chimney, and keeps 50 thereby the glass comparatively cool, so that one cause of breakage—namely, the great difference in the temperature between the internal and external surfaces of the glass when a current of cold air strikes upon the glass— 55 is to a great extent eliminated.

I have also ascertained that a better light is produced where this auxiliary flue is employed than where the chimney is used without it.

The lower portion of the flue should be large 60 enough for the widest flame desired, as there will be a tendency in the flame to be somewhat narrowed on account of the concentration of the draft toward the center of the chimney, and this of course prevents to some extent the 55 irregular jets of flame, caused by bad trimming of the wick, from infringing upon the walls of the chimney and thereby breaking it.

I am aware of Patents No. 70,935, to Addison; No. 40,820, to Albertson; No. 230,466, to 70 Butcher; No. 307,406, to Miller; No. 112,446, to Griswold, and No. 161,339, to Johnson; but while each describes a lamp-chimney with some sort of a tube arranged in connection with it, neither of them shows a sub-caliber tube having 75 a bell-shaped bottom and imperforate wall arranged within a lamp-chimney and projecting well above it, all of which characteristics I have found essential in order to get the best results, which I have described, whereby more 80 and better light is got from the same oil and less chimneys are broken than before.

Having thus fully described my invention, I claim and desire to secure by Letters Patent 85 of the United States—

The combination, with a lamp burner and chimney, of a bell-mouth flue or tube extending above the top of the chimney and a support for the same, said support being composed of elastic wires, twisted as shown, the ends being 90 formed into a spring-clamp, *f*, adapted to clasp the cone of the burner.

CHARLES L. INGALLS.
